UNITED STATES PATENT OFFICE.

JOSEPH H. DILLON, OF WILMETTE, ILLINOIS, ASSIGNOR TO DILLON PULLEY CO., OF CHICAGO, ILLINOIS, A CORPORATION OF ILLINOIS.

PULLEY.

Application filed February 18, 1922. Serial No. 537,398.

My invention relates to builder's hardware, and more specifically to an improved pulley and support therefor, constituting an article of manufacture commonly referred to as an entirety as a sash pulley.

One primary object of the invention is to improve the functioning of devices of this sort.

A more specific object is to provide guiding baffles of a better and more efficient shape than have heretofore been constructed.

Another primary object is to diminish the cost of the finished article without decreasing either its strength or durability.

Another object closely identified with the one just stated is to form the entire assembly of sheet metal only, there being no cast metal in the entire device, which, however, has a rigidity approximating that of a casting and more than adequate for the service for which it is intended.

Another object is to simplify the shape of the parts and simultaneously provide a more positive fastening engagement between the parts.

A more specific object is to form the entire side, end and top walls of the casing of a single piece of material.

Further objects and advantages of the invention will become apparent as the description proceeds.

In the accompanying drawings,

Figure 1 is a plan view of a blank from which the casing is to be formed;

Fig. 2 is a sectional view of the finished article;

Fig. 3 is a plan view of the casing bottom; and

Fig. 4 is a detailed view illustrating a modification.

The disclosure herein is in the nature of an improvement on Patent 1,224,152 to Joseph J. Dillon, May 1, 1917.

In the embodiment of my invention selected for illustration, a simple flat sheet-metal face plate 10 is provided, apertured at 12 to receive fastening screws, and having a large aperture at 14 to receive the pulley casing, and a small aperture at 16 to receive fastening lugs.

A sheet metal blank 18 is bent around its center line, while the periphery thereof

from substantially the point 20 to the corners 22 is being curved in over the narrow area 24 indicated by dotted lines in Figure 1, the outer marginal portions 26 and 28 being kept in a parallel plane with side portions 30. The folded blank, completed by wrapping portion 28 over portion 26 as clearly indicated in Figure 2 will have an open bottom, shaped to fit accurately inside the cup-shaped bottom 32, a small central area near the lower edge indicated by dotted line 33 being pressed inward out of the plane of side portion 30 to fit the offset 36 in the bottom. Apertures 38 are provided to receive pintle 40 passing through the device and riveted outside the casing at both ends. Pintle 40 does not rotate, and pulley 42 is provided with a sleeve or bushing 44, preferably of such material that it will slide on pintle 40 with relatively negligible friction. Pulley 42 itself is formed of duplicate sheet metal stampings apertured at 46 for the reception of annular sheet metal riveting devices 48.

The bottom 32 is apertured at 34 and 36 to guide a cord running over the pulley, the edges of the apertures being rolled back to provide flaring mouths assuring a minimum of friction on the cord. It should be noted that both these guiding apertures are so far from the points where the cord comes into contact with the pulley, that the cord, even when slack, cannot possibly ride up on the edge of the pulley groove and cut itself. Furthermore, the space 48 between the portion of the pulley carrying the cord and the enclosing casing is so proportioned with respect to the diameter of the cord, that the cord cannot possibly jump far enough up toward either edge of the pulley groove to do itself any harm.

From opposite sides of the casing tabs 50 are struck up and bent inwardly as clearly shown in Fig. 2. In threading a cord into a completely enclosed pulley, a "mouse" is usually required, and in the absence of such special equipment, it is difficult and often impossible to thread the pulley. In a device constructed according to my invention, the full size cord may be thrust into aperture 34 and pushed around the pulley guided by its contact with the casing. This

bends the advancing end of the cord into a curve, from which it will not completely straighten so that the end will follow the pulley past aperture 36 coming into abutment with the center of bottom 32. Lugs 50 function as baffles and are positioned where the advancing end of the cord will strike them and be deflected away from the pulley directly through aperture 36. It is thus possible to thread the pulley much more quickly than could be done with a "mouse," by simply pushing the end of the cord in at aperture 34 and continuing to push until the other end comes out at aperture 36. 15 Bottom 32 is preferably a very snug or pressed fit on the casing, and the assembled casing is also a very tight or pressed fit in the face plate 10. The outer portions 26 and 28 of the casing blank terminate in lugs 20 52, which in the assembled device lie face to face and pass through apertures 16 in the base plate. The casing may be thrust into aperture 14 with its lowest corner foremost, until the downturned edge of aperture 25 34 hooks over the bottom of aperture 14. It may then be rotated around the lower edge of aperture 14 until lugs 52 pass through aperture 16, to be bent over or clinched as clearly shown in Fig. 2, and, if desired, spot 30 welded to plate 10. In this position there is gripping engagement at the bottom of aperture 14 between the lip of aperture 34 and the base plate to prevent movement in one direction, and between shoulder 36 and 35 the other side of the base plate to prevent movement in the other direction. The clinching of lugs 52, therefore, completes the operation of fastening the parts in assembled relation, no fastening members in addition 40 to the parts themselves being required.

It will be obvious that any suitable method of deforming lugs 52 to fasten the parts in assembled relation may be employed. In Fig. 4 I have illustrated one alternative arrangement in which substantially half of each lug is bent over at right angles about an axis perpendicular to plate 10 to form a shoulder hooking over the plate.

Without further elaboration, the foregoing will so fully explain the gist of my invention, that others may, by applying current knowledge, readily adapt the same for use under various conditions of service, without eliminating certain features which 50 may properly be said to constitute the essential items of novelty involved, which items are intended to be defined and secured to me by the following claims.

- 60 I claim:
1. In a device of the class described, a sheet metal face plate having an aperture, and a sheet metal casing thrust partly through said aperture.
  - 65 2. In a device of the class described, an apertured sheet metal face plate, a casing

thrust partly through said aperture, a pulley in said casing, said casing projecting through said aperture to house the portion of the pulley projecting past the plane of said face plate, and apertures in the bottom of said casing in tangential alignment with the periphery of said pulley. 70

3. In a device of the class described, a face plate having an aperture, and a sheet metal casing thrust partly through said 75 aperture, said face plate being a driving fit on said casing.

4. In a device of the class described, a face plate having an aperture, a casing thrust partly through said aperture, said casing 80 having shoulders on its sides adjacent one end of said aperture, and a projection on its bottom spaced from the plane of said shoulders by substantially the thickness of the face plate and engaging the opposite side 85 thereof.

5. In a device of the class described, a bottom having an upturned peripheral lip, said lip and bottom being offset inwardly adjacent one end, and an open bottomed casing 90 with its edge entered inside said lip.

6. In a device of the class described, a bottom having an upturned peripheral lip, said lip and bottom being offset inwardly adjacent one end, an open bottomed casing with 95 its edge entered inside said lip, and an apertured face plate fitting over one side of said casing, and the inwardly offset portion of said bottom.

7. In a device of the class described, a 100 bottom having an upturned peripheral lip, said lip and bottom being offset inwardly adjacent one end, an open bottomed casing with its edge entered inside said lip, an apertured face plate fitting over one side of said 105 casing and the inwardly offset portion of said bottom, said offset engaging one side of said face plate to limit relative movement between the parts in one direction, and a downward projection on said bottom engaging the 110 other side of said face plate to limit movement in the other direction.

8. In a device of the class described, a bottom having an upturned peripheral lip, said lip and bottom being offset inwardly adjacent one end, an open bottomed casing with 115 its edge entered inside said lip, an apertured face plate fitting over one side of said casing and the inwardly offset portion of said bottom, said offset engaging one side of said face plate to limit relative movement between the parts in one direction, and a downward projection on said bottom engaging the other side of said face plate to limit movement in the other direction, said downward projection constituting a lip defining a guide 120 aperture in said bottom.

9. In a device of the class described, a face plate having an aperture, a casing thrust partly through said aperture, and a pulley in 125

said casing extending on both sides of the plane of said face plate, said casing having a closed front side covering the portion of said pulley projecting through said face plate.

10. In a device of the class described, a face plate having an aperture, a casing thrust partly through said aperture, a pulley in said casing extending on both sides of the plane of said face plate, and apertures in said casing for guiding a cord passing over said pulley in lines substantially parallel to said face plate.

11. In a device of the class described, a face plate having an aperture, a casing thrust partly through said aperture, a pulley in said casing extending on both sides of the plane of said face plate, and apertures in said casing for guiding a cord passing over said pulley, said apertures being remote from where the cord leaves the pulley.

12. In a device of the class described, a sheet metal casing, a pulley therein, and lugs inside the casing bent in from the sides thereof to guide a cord passing partly round the pulley.

13. In a device of the class described, a sheet metal casing, a pulley therein, apertures in said casing for the entry and exit of a cord passing partly round the pulley, and guides inside the casing adjacent the exit aperture for directing a free end of cord out through said aperture.

14. In a device of the class described, a sheet metal casing, a pulley therein, apertures in said casing for the entry and exit of a cord passing partly round the pulley, and guides adjacent the exit aperture for directing a free end of cord out through said aperture, said guides consisting of lugs bent in from the side walls of said casing.

15. In a device of the class described, a pocket having a substantially plane mouth and a substantially semi-circular imperforate bottom, a pulley in said pocket, a pintle for said pulley substantially concentric with said bottom, and a cover closing said pocket.

16. In a device of the class described, a one-piece pocket having a substantially plane mouth and a substantially semi-circular bottom, a pulley in said pocket, a pintle for said pulley substantially concentric with said bottom, and a cover closing said pocket, said cover having apertures at its ends remote from the periphery of said pulley for guiding a cord into and out of said pocket.

17. A pulley casing formed of a single sheet of material, said casing being in the form of an open mouthed pocket, having one edge integral, and the remaining edges sealed by beading the periphery of one side wall around the edge of the other, and a cover

gripping the edges of the pocket to brace its walls.

18. A pulley casing formed of a single sheet of material, said casing being in the form of an open mouthed pocket, having one edge integral, and the remaining edges sealed by beading the periphery of one side wall around the edge of the other, the peripheral portions used to seal the pocket extending out to form attaching lugs.

19. In a device of the class described, in combination, a face plate having an aperture, a casing thrust partly through said aperture, and a pulley in said casing extending on both sides of the plane of said face plate, said casing housing said pulley on both sides of the plane of said face plate.

20. In a device of the class described, in combination, an apertured face plate, a casing thrust partly through said plate, a downward projection on the bottom of said casing engaging the front of said plate, side shoulders near the bottom of said casing engaging the rear of said plate, and fastening means near the upper end of said aperture for holding the parts in assembled position.

21. In a device of the class described, in combination, an apertured face plate, a casing thrust partly through said plate, side shoulders near the bottom of said casing engaging the rear of said plate, and fastening means near the upper end of said aperture for holding the parts in assembled position.

22. In a device of the class described, in combination, an apertured face plate, a casing having a closed front side thrust partly through said plate, projections near the bottom of said casing engaging the rear of said plate, and fastening means near the upper end of said aperture for holding the parts in assembled position.

23. In a device of the class described, a sheet metal casing, a pulley therein, and lugs inside the casing bent in from the sides thereof to guide a cord passing partly around the pulley, said lugs lying out of contact with the cord after it passes outside the casing and is drawn taut.

24. In a device of the class described, a casing, a pulley within said casing, apertures in said casing for receiving a cord, said apertures encircling said cord only at points beyond where the cord leaves the pulley, and a baffle struck in from said casing adjacent the edge of one of said apertures to prevent the end of a cord from following the pulley groove past said aperture.

In witness whereof, I hereunto subscribe my name this 15 day of February, 1922.

JOS. H. DILLON.
